UNITED STATES PATENT OFFICE.

CHARLES HAMMER, OF HOLLIS COURT BOULEVARD, NEW YORK.

CAP.

Application filed November 29, 1922. Serial No. 603,990.

To all whom it may concern:

Be it known that I, CHARLES HAMMER, a citizen of the United States, residing at Hollis Court Boulevard, in the county of Queens 5 and State of New York, have invented certain new and useful Improvements in Caps, of which the following is a specification.

This invention relates to sheet metal caps for glass containers such as jars and bottles, 10 in which locking projections of wedge form are formed in the skirt or flange of the cap adapted to cooperate with locking projections on the container neck, whereby the closure can be screwed onto the jar to form a 15 tight seal, and also readily removed from the same.

The object of the present invention is the provision of a closure of this character with a special form of projection, so pressed inwardly of the skirt or flange as to provide 20 an effective sealing wall or face at the upper part or edge of the projection, extending for a very considerable length of each projection, and thus provide a large area of sealing surface 25 to engage the thread or other locking projection on the container.

A further object of the invention is the provision of an improved cap in which the locking projection will have its wide portion 30 of its working face adjacent to the lower part of the closure, or at the initial entering end of the projection as it is screwed down on the jar.

A still further object of the invention is to 35 provide a closure with a locking projection narrow and deep at the lower entering end thereof and wide and shallow toward the opposite end.

In my prior Patent 1,160,596 dated November 16, 1915, upon which the present cap 40 is an improvement, the locking projections are narrow and shallow at their entering end adjacent to the beaded edge and wide and deep toward or at their opposite end, where- 45 as in the present improved cap the locking projections of wedge form are narrow but deep at their entering end and wide but shallow toward or at their opposite end, in consequence of which a more effective holding, locking or sealing of the cap upon the 50 locking projections or threads of the container neck is obtained because the thread or projection of the jar neck is more likely, for the reasons hereinafter stated, to be more uniformly formed at those points where the 55 entering ends of the projections finally seat.

Therefore, one of the objects of the pres-

ent improvement is the provision of a metal cap, which may be made of relatively thin sheet metal having a relatively shallow flange or skirt provided with reinforcing corrugations and a strengthened or reinforced— 60 as a beaded, rolled or curled—lower edge, and the flange of which cap is provided with a projection or projections narrow but deep at its entering end and wide but shallow 65 toward its opposite end, which shallow portion substantially fills the space between the corrugations and the beaded lower edge, and in which the projections are of wedge form having a helical or inclined sealing, locking 70 or working upper face or edge, and a relatively straight—in the direction of its length—lower edge which may be substantially parallel or in close proximity to the lower edge or strengthened edge of the cap 75 whereby all the advantages of the form of projections shown in my prior patent are still obtained with the additional advantage of an increased locking efficiency.

In the accompanying drawings showing 80 one embodiment of my invention, Figure 1 shows the closure applied to a jar; Fig. 2, is a plan view partly broken away to show a jar thread, and also to show the upper wall of a projection; Fig. 3 is a fragmentary view of the jar and closure; Fig. 4 is a partial view of the closure inverted; Fig. 5 is a cross section on the line 5, 5 of Fig. 3; Fig. 6, is a cross section on line 6, 6 of Fig. 3; Fig. 7 is a cross section on line 7, 7 of Fig. 90 3; and Fig. 8 is a cross section on line 8, 8 of Fig. 3.

Before explaining in detail the present improvement and mode of operation thereof, I desire to have it understood that the 95 invention is not limited to the details of construction and arrangement of parts which are illustrated in the accompanying drawings, since the invention is capable of other embodiments, and that the phraseology 100 which I employ is for the purpose of description and not of limitation.

In the drawings this improved closure is shown comprising a top 2 and a skirt 3, that is preferably provided with a strengthened or reinforced lower edge, shown as a bead or rolled edge and with reinforcing corrugations 4'. In the skirt I provide a plurality of projections 5, of wedge form by forcing inwardly the wall of the skirt 3. 110 Four of these projections are shown adapted to cooperate with divided threads 6 on the jar 1, which are suitably inclined.

Each of these projections 5 is shown as substantially of wedge form, and is provided practically with three walls, an upper wall 7 facing the top of the cap, an inner or vertical wall 8, of slightly curved formation and a bottom wall 9. This improved projection is deepest where the side wall 8 is narrowest, which is at the entering end 10 of the projection, see Fig. 4. The depth 10 of the projection gradually decreases as the wall 8 approaches the skirt or flange wall 3 from this deep end 10 toward the other end portion. The upper wall 7 is widest at this deep end and remains wide for a considerable distance, and then gradually tapers off thus forming a shelf or working face 7, of considerable area adapted to engage the lower wall of the thread 6 on the jar, which will preferably have its lower wall at a very abrupt angle relatively to the neck of the jar.

The lower wall 9 of the projection gradually tapers toward the shallow end and practically merges into the skirt wall, so that the relative straight side wall 8 is inclined outwardly at the larger end, as indicated in the sectional views, Figs. 5-8.

Thus it will be seen that each of the projections or wedges of the closure is deep 30 and narrow at one end, which is the lower end adjacent the bead of the closure, and becomes wider from this end toward the other end, where it becomes more shallow practically merging into the cylindrical wall 3 of the skirt. The threads or lugs 6 on the jar 1, are preferably inclined at the same angle as the upper wall 7 of each projection. When the cap is applied the narrow deep end portion 10 passes below the upper end portion of each jar thread 3, with its upper wall 7 engaging the lower wall of the thread 6. As the cap is turned these engaging or working walls act as a screw thread and force the cap downwardly until 40 its top 2 engages the top edge of the jar, the cap usually being provided with a suitable liner. Thus, it will be seen that the smaller end 10 of the projection has advanced and moved downwardly and engages 50 at the lower portion of each jar thread 6, instead of the upper portion adjacent to the top of the jar.

It has been found in practise that jars 55 with threads sometimes have the upper end portion of the thread broken or chipped while the lower portion adjacent the usual bead or shoulder 11 on the jar is less likely to be damaged as it is protected by this shoulder. Therefore a better sealing is insured because the jar thread is in better condition at its lower portion. Furthermore 60 the main sealing portion of each projection being at the lower part of the skirt of the closure, the latter can yield more to provide 65 for jars that are irregular and not a true

circle, than if the sealing portion of the projection was at the upper part or near the top of the cap, while at the same time the deep part of the projection is more effectively strengthened by reason of the 70 fact that it is closer to the strengthened or curled or beaded edge of the cap, so that it is not so likely to be distorted out of its proper locking position and thus the cap can be very effectively used for re-sealing 75 purposes. It will be further observed that these improved locking projections, narrow but deep at their entering ends and wide but shallow toward their opposite ends, are 80 so located in the present instance that the lower edge of each projection is relatively close to and may be substantially parallel with the lower or strengthened or reinforced edge of the cap, while the upper or working or sealing edge of the projection is inclined 85 upwardly toward the top of the cap, thus forming in this sense a threadlike or helical working edge with the wider portions of the locking projections preferably substantially filling the space between the beaded 90 edge and the corrugations of the cap so that I am able to provide a shallow flange cap having all the meritorious features of the cap of the patent referred to as well as certain advantages thereover. As the holding 95 efficiency of each projection is usually greatest where it is the deepest, it follows that by having the deepest part of a projection at its shallow or entering end it will engage under the glass thread or projection 100 when the cap is first started onto the container and continues to engage thereunder throughout the entire length of the glass thread so that the cap is drawn down onto the container during all of its rotary movement home, and consequently the container is very effectively sealed.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all the forms in which it may be made, or all of the modes of its use, I claim:

1. A sheet metal closure for containers and comprising a top and a flange, the flange being provided with an inwardly extending projection narrow and deep at one end and wide and shallow toward the other end.
2. A sheet metal closure for containers and comprising a top and a flange provided with a beaded lower edge, the flange being provided with an inwardly extending projection narrow and deep at one end and wide and shallow toward the other end with the

lower portion of the projection at the said deep end portion thereof in close proximity to the bead.

3. A sheet metal closure for a threaded top container, and comprising a top and a flange provided with an inwardly extending projection narrow and deep at one end and wide and shallow toward the other end portion, the upper wall of the projection 10 facing the top of the cap extending substantially perpendicular to the adjacent cap flange thereby to provide a comparatively flat wall for engagement with the under wall of the container thread.

15 4. A sheet metal closure for a threaded top container, and comprising a top and a flange provided with an inwardly extending projection narrow and deep at one end and wide and shallow toward the other end, the 20 upper wall of the projection facing the top of the cap extending substantially perpendicular to the adjacent cap flange thereby to provide a comparatively flat spiral wall for engagement with the under wall of the 25 container thread, and which cap wall is of maximum width at its lower end adjacent the flange edge.

5. A sheet metal closure for containers and comprising a top and a skirt, provided 30 with an inwardly extending projection, which is deep at one end portion adjacent the lower edge of the skirt and shallow toward the opposite end of the projection.

6. A sheet metal closure for containers and comprising a top and a skirt provided 35 with an inwardly extending projection narrow and deep at one end portion adjacent to the lower edge of the cap and shallow toward the opposite end of the projection.

40 7. A sheet metal closure for containers, and comprising a top and a flange provided with a reinforced lower edge, and an inwardly extending projection narrow and deep at one end portion adjacent to the reinforced edge and wide and shallow toward the other end portion.

45 8. A sheet metal closure for a container having locking projections and comprising a top and a flange, the flange having an inwardly extending projection, narrow and deep at one end and wide and shallow toward the other end, the upper wall of the projection facing the top of the cap extending substantially perpendicular to the adjacent cap flange from the deep end portion for the major part of the projection, thereby to provide a comparatively flat elongated wall for engagement with the under wall of the container projections.

50 9. A sheet metal closure for a container having locking projections and comprising a top and a flange provided with a beaded lower edge and an inwardly extending projection, narrow and deep at one end and wide and shallow toward the other end with

the lower portion of the projection in close proximity to the bead, the upper wall of the projection facing the top of the cap extending substantially perpendicular to the adjacent cap flange from the deep end portion 55 for the major part of the projection, thereby to provide a comparatively flat elongated wall for engagement with the under wall of the container projections.

10. A sheet metal closure for containers and comprising a top and a depending flange provided with an inwardly extending wedge-formed projection deep at its entering end and shallow toward its opposite end.

15 11. A sheet metal closure for containers and comprising a top and a depending flange provided with an inwardly extending wedge-formed projection deep at its entering end and wide toward its opposite end.

20 12. A sheet metal closure for containers and comprising a top and a shallow depending flange having reinforcing corrugations and an inwardly extending wedge-formed projection having a deep entering 25 end and a shallow portion toward its opposite end with the upper edge of the projection inclined in the direction of its length toward corrugations.

25 13. A sheet metal closure for containers and comprising a top and a shallow depending flange having a beaded lower edge and provided with an inwardly extending wedge-formed projection having a deep entering 30 end adjacent to such beaded edge and a shallow portion toward its opposite end with the upper edge of the projection inclined in the direction of its length.

35 14. A sheet metal closure for containers and comprising a top and a depending flange provided with a plurality of inwardly extending wedge-formed projections, each having a narrow, deep entering end in proximity to the lower edge of the flange, a shallow portion toward its opposite end and in the direction of its length an inclined upper working face, the lower face of the projection being in close proximity to the lower edge of the flange.

40 15. A sheet metal closure for containers and comprising a top and a shallow depending flange having reinforcing corrugations and a reinforcing beaded lower edge and provided with an inwardly extending wedge-formed projection having a deep 45 entering end adjacent to the beaded edge and a shallow portion substantially filling the space between the beaded edge and the corrugations with the upper edge of the projection inclined in the direction of its length.

50 16. In a sheet metal cap comprising a top and a depending flange said flange having inwardly pressed wedge-formed projections therein, each having in the direction of its 55 length.

length an inclined upper working wall, a lower wall and a vertical connecting wall, all of said walls tapering off and merging into the flange of the cap toward the rear end of the projection and forming a deep entering end to the projection in proximity to the lower edge of the cap.

17. A sheet metal cap comprising a top and a depending flange having spaced reinforcements, said flange having between said reinforcements, a plurality of inwardly pressed wedge formed projections each comprising an upper inclined working wall, a lower wall and a vertical connecting wall, all of said walls tapering off and merging into the flange of the cap toward the rear end of the projection and forming a deep entering end in proximity to the lower edge of the cap.

18. The method of making a sheet metal cap having a top and a depending flange which consists in subjecting the flange to such pressure that a wedge formed projection is formed therein extending circum-

ferentially of the flange, deep and narrow at its lower entering end and wide and shallow toward its rear end.

19. The method of making a sheet metal shallow flange cap which consists in forming a cup-shaped blank comprising a top and a shallow depending flange, then subjecting the flange to pressure thereby to form spaced reinforcements, and therebetween a plurality of wedge-formed projections extending circumferentially of the flange, each having in the direction of its length an upper inclined wall, a lower wall and a vertical connecting wall all tapering off and merging into the flange of the cap toward the rear end of the projection, the pressure being such that the projection has a deep lower entering end in proximity to the lower edge of the flange.

Signed at 1822 Park Row Building, New York city, N. Y., this 27th day of November, 1922.

CHARLES HAMMER.
